UNITED STATES PATENT OFFICE.

CARL A. STROM, OF FLORAL PARK, NEW YORK.

WINDOW-SASH LOCK.

Application filed September 25, 1922, Serial No. 590,353. Renewed May 25, 1925.

To all whom it may concern:

Be it known that I, CARL A. STROM, a citizen of the United States, and resident of Floral Park, in the county of Nassau and 5 State of New York, have invented certain new and useful Improvements in Window-Sash Locks, of which the following is a full, clear, and exact specification.

This invention relates to window sash locks, and has for its object to provide 10 simplified and improved means for locking both the upper and lower sashes in different positions, so that they cannot be opened farther from the outside.

15 A special object of this invention is to provide for locking both sashes by a single catch having two locking tongues or members adapted to simultaneously engage different locking means for securing both 20 sashes in adjusted positions to a fixed part of the window frame. Other objects will appear as the description proceeds.

The invention will be first hereinafter described in connection with the accompanying 25 drawings, which constitute part of this specification, and then more specifically defined in the claims at the end of the description.

In the accompanying drawings, wherein 30 similar reference characters are used to designate corresponding parts throughout the several views:

Figure 1 is a perspective view of portions 35 of upper and lower window sashes and the beading separating them on the frame, one of the locking devices constructed substantially in accordance with this invention being attached to the meeting rail of the lower sash, and slotted strips to be engaged by said 40 locking device or catch being shown attached to the upper sash and the beading.

Figure 2 is a front elevation drawn to a larger scale of the same parts, parts being in section.

45 Figure 3 is a longitudinal section through the sashes showing the locking means in side elevation, as when looking from the right in Figures 1 and 2, and

Figure 4 is a detailed view of the catch 50 in unlocked position.

The upper and lower sashes of an ordinary window are indicated at 1 and 2, respectively, in Figures 1, 2 and 3, and the usual beading for separating the grooves for 55 said sashes is indicated at 3. To the inner face or edge of said beading a strip 4,

preferably of metal, is secured in any suitable manner, as by screws 5, said strip having slots 6 formed at intervals along the same and the face of the beading below said 60 slots being recessed, as at 7, Figure 2. The strip 4 is of a width to lie between the upper and lower sashes without interfering with the free movement thereof. Said strip 65 preferably extends from a point adjacent the position of the meeting rails of the sashes when closed to a point far enough above the same to permit of several different adjustments of the lower sash.

An angle strip 8 is similarly fastened, as 70 by screws 9, to the front face of the frame of the upper sash 1, and a series of slots 10 are formed in the forwardly projecting flange 11 of said angle strip. Said strip 8 75 may extend any desired distance along the vertical side member of the upper sash and have any desired number of slots 10 in its flange. The strips 4 and 8 are thus arranged in close proximity to each other, with the flange 11 of the strip 8 occupying 80 a plane slightly to the rear and at the right of the strip 4 as shown in Figures 1 and 2.

A double catch 12, having two locking tongues 13 and 19, is pivoted at 14 in a bracket 15 which is secured to the upper 85 face of the meeting rail 16 of the lower sash 2 by screws 17. Said catch is preferably made of sheet metal of suitable shape to form the pivoted shank 18 and the two 90 tongues or hooks 13 and 19, and the sheet 95 of metal is bent at 20 to bring the upper end portion of the catch, which carries the upper tongue of hook 19 into the plane of the slots 10 in the flange 11 of the strip 8, while the lower portion of said catch, which 95 carries the lower tongue or hook 13 is arranged in the plane of the slots 6 in the strip 4 attached to the beading 3. It will also be noted that the lower hook or tongue 13 is longer or extended farther to the left than 100 the upper hook 19, so that said hooks are capable of simultaneously engaging slots in the strips 4 and 8, as best shown in Figures 1 and 2.

For actuating the catch a finger piece 21 105 may be bent forwardly at the edge thereof preferably about in the position shown, and to lock the catch in its strip engaging position a pawl 22 is provided, the same being pivoted at 23 to the bracket 15 and adapted 110 to engage in a notch 24 in the edge of the catch, see Figure 2. Said pawl is also

preferably formed with a forwardly bent finger piece 25.

When the catch 12 is in unlocking position, as shown in Figure 4, the lower sash 5 may be raised and lowered at will, and the same is true of the upper sash. When it is desired to lock said sashes in partially opened or fully closed position, the catch is moved into engagement with those of the 10 slots 6 and 10 in the strips 4 and 8, respectively, which are at the time in line with the hooks on said catch, and the sashes are thus secured against upward or downward movement because the hook or tongue 19 15 fastens said sashes together, while the hook or tongue 13 locks both to the fixed bead- ing 3.

I claim:

1. A window sash lock having a catch pivoted to swing thereon, the free end of said catch having two integral locking members extending in the same direction and offset laterally one from the other to simultaneously fasten both the lower and upper sashes 25 of a window in adjusted positions.

2. A window catch to be pivotally attached to one window sash and having on its free end portion two integral locking members extending in the same direction 30 for simultaneously fastening the other sash thereto and both sashes to a fixture, the portion of the catch carrying one of said locking members being offset laterally from the portion carrying the other locking member 35 for the purpose specified.

3. A sash lock comprising a bracket, a catch pivoted at one end to said bracket and having a locking hook on its free end portion and a notch in its rear edge, and a retaining pawl pivoted on said bracket in rear 40 of said catch, and adapted to be swung to bring its free end into engagement with said notch in the rear edge of the catch; when the latter is in locking position, for holding 45 said catch in that position.

4. The combination with slotted strips to be secured to one of a pair of window sashes and to a part of a window frame, respectively, of a catch to be pivotally secured at 50 one end to the other sash and having two integral locking members on its free end portion for simultaneously engaging said slotted strips for fastening both sashes in adjusted positions, one of said locking members being carried by the extreme free end 55 portion of the catch and said extreme end

portion and locking member carried thereby being offset laterally for the purpose specified.

5. The combination with slotted strips to be secured to one of a pair of sashes and to a part of a window frame, respectively, and arranged in parallel vertical planes, of a catch to be pivotally secured to the other sash to swing in a vertical plane and having 60 two integral locking hook-shaped members extending in the same direction and offset laterally one from the other on its free end portion for simultaneously engaging said slotted strips and fastening both sashes in 65 adjusted positions.

6. The combination with slotted strips to be secured to one of a pair of sashes and to a part of a window frame, respectively, and arranged in parallel vertical planes, of a catch to be pivotally secured to the other sash and having two integral locking hook-shaped members of different lengths on its free end portion and extending in the same 70 direction and offset laterally one from the other for simultaneously engaging said slotted strips and fastening both sashes in 75 adjusted positions.

7. The combination with a slotted strip to be secured to the beading between the upper and lower sashes of a window, of an angle strip to be secured to the upper sash and having a forwardly extending slotted flange arranged in a plane parallel to that of said slotted strip on the beading, and an integral 80 double catch to be pivoted to the lower sash and having two integral hook-shaped locking members extending in the same direction and offset laterally one from the other to simultaneously engage both slotted strips. 85

8. The combination with a slotted strip to be secured to the beading between the upper and lower sashes of a window, of an angle strip to be secured to the upper sash and having a forwardly extending slotted flange 90 arranged in a plane parallel to that of said slotted strip on the beading, and an integral double catch to be pivoted to the lower sash and having two integral hook-shaped locking members extending in the same direction and offset laterally one from the other to simultaneously engage both slotted strips. 95

In testimony whereof I have signed my name to this specification.

CARL A. STROM.
